UNITED STATES PATENT OFFICE.

WILLIAM H. BARTLETT, OF WORCESTER, MASSACHUSETTS.

DESIGN FOR A BADGE.

SPECIFICATION forming part of Design No. 22,636, dated July 18, 1893.

Application filed April 19, 1893. Serial No. 471,042. Term of patent 14 years.

To all whom it may concern:

Be it known that I, WILLIAM H. BARTLETT, a citizen of the United States, residing at Worcester, in the county of Worcester and State of Massachusetts, have invented and produced a new and original Design for a Badge, of which the following, together with the accompanying drawings, is a full, clear, and exact specification.

10 Figure 1 is a front view of a badge showing my design, and Fig. 2 is a view of the reverse side of the medal portion.

The leading features of my design consist of the ornamentation on the pendent medal 15 and heading, as illustrated; the same comprising, on the medal, a circular disk bearing upon its center the representation of two men facing each other in standing position, and grasping hands. This central field is 20 rounded by an annular border or margin adapted to receive a suitable inscription. Said border is separated from the central field

by a beaded circle, and its exterior is ornamented by circumscribing edging-lines. Upon the reverse side of the disk the badge is provided with a plain surface adapted for receiving an inscription, and surrounded by a narrow circular border, as shown in Fig. 2. The hanger or ribbon for the suspension of the badge or medal is ornamented with parallel 25 stripes. Across the top of the ribbon or hanger there is a heading or pin-bar having a narrow beaded border, and a plain surface inclosed thereby suitable for containing a name or number. 30

35

What I claim is—

The design for a badge, substantially as herein shown and described.

Witness my hand this 17th day of April, A. D. 1893.

WILLIAM H. BARTLETT.
